TANK CLEANING DEVICE

James A. Cronin, Berkeley, Calif., assignor to
Standard Oil Company of California, San
Francisco, Calif., a corporation of Delaware

Application February 20, 1933, Serial No. 657,543

9 Claims. (Cl. 299—73)

This invention relates to tank cleaning devices, and particularly to one which is adapted to be installed in a ship's tank and used to clean off the coating of oil, scale and sediment which adheres to the sides and bottom after the cargo has been pumped out.

There are a number of mechanical devices as well as various methods or systems by which they may be operated to accomplish the purpose of 10 cleaning the interior of a tank of this type. Most of these machines are relatively costly to build and maintain due to the corrosive conditions on board ship and to the roughness with which they may be handled. Furthermore, the complications of rotating gearing, sleeves, packing, and the like, are a constant source of trouble and annoyance, if not actual delay, which is of great importance, as demurrage on a tank ship laid up for cleaning is very expensive.

20 A still further objection to previous apparatus is its bulk and weight, most of the machines having long unwieldy tubular sections adapted to be projected into a tank, with heavy mechanisms thereon, which require the use of special 25 lifting and handling equipment. Special hatch covers are usually required, and a source of power, such as compressed air, for operating the mechanism. Also, the automatic type of cleaning equipment washes all parts of the tank interior 30 without regard to the requirements for such action. Thus parts which require but little attention are repeatedly and uselessly contacted, while very dirty and inaccessible sections may not be adequately cleaned.

35 It is an object of this invention to provide a very simple tank cleaning device which may be used for the controlled internal washing of ships' tanks and the like.

40 A further object is to provide an apparatus of this nature which is capable of being easily handled without the use of slings, winches and the like, and which may be dismantled and stowed in a small space between periods of use.

45 Another object is to provide a universal tank cleaning device in which there are no accurately fabricated or machined parts, so that replacements and repairs may be easily made with materials at hand on every cargo ship, whether or 50 not it is a tank vessel.

55 Another object is to provide a tank cleaning device which is capable of intelligent direction by an operator so that particularly dirty or inaccessible parts of a tank will receive proper cleaning while more easily cleaned surfaces will

not be repeatedly contacted for long periods and to no advantage.

These and other objects will be more fully apparent from the description which follows, and from the accompanying drawing, which forms a part of this specification and illustrates a preferred embodiment of this invention.

In the drawing:

Figure 1 is an elevation of a preferred form of the apparatus installed in a ship's tank.

Figure 2 is a detail of a nozzle fitting or connector which is supported in the tank, and to which a conventional fire hose and a nozzle may be attached.

Figures 3 and 3a are side and front elevations, 15 respectively, of a carrier fitting which may be used to support the nozzle fitting on a wire cable or a rod in the tank.

Figure 4 is a detail of an extension handle which is adapted to direct the carrier and washing nozzle 20 as desired by the operator.

Referring to Figure 1, the numeral 11 represents the hull of a tank ship in which is formed a tank space 12. The details of frames, stringers, brackets, piping, valves and the like, have been 25 omitted for the sake of clarity, but are well known to those skilled in the art. A hatch 13 is provided in the deck forming the top of the tank 12, and a ladder 14 leads downwardly therefrom to the bottom of the tank. Side or summer tanks may 30 be mounted at the side of the hull as at 15.

In the preferred embodiment, a steel wire cable 16 is secured at the bottom of the tank, as to a frame, by means of a C-clamp 17, or any other means, and leads upwardly through the hatch 13. 35 The upper end of cable 16 may be secured to the superstructure of the ship or to a temporary A-frame (not shown) over the hatch opening. Suitable tightening means such as a turn buckle (not shown) may be used to draw the cable taut.

Part way up cable 16 is attached a conventional cable clamp or clip 18, which may be adjusted to suit along the length of the cable, and which forms a downward motion stop for the nozzle carrying and directing apparatus. A steel washer 19, of suitable diameter may be slipped over the cable above clamp 18 to act as a thrust washer or bearing. Above the washer 19 is shown a nozzle carrier guide 20, which may be made from two pieces of brass or steel pipe 21 and 22 welded 45 together at right angles as shown in Figure 3. Pipe 21 is adapted to slide freely on guide cable 16 and is of appreciable length, say three feet, while pipe 22 forms a short horizontal bearing 50 for a stub shaft on the nozzle fitting 23.

Nozzle fitting or connector 23 is detailed in Figure 2, and consists of a suitable pipe nipple 24, which is threaded at both ends to receive a standard fire hose nozzle and hose coupling, respectively. A stub shaft or stud 25 is welded to one side of nipple 24 and is of such diameter as to be journaled in bearing 22 of the carrier guide 20. The outer end of stub shaft 25 is drilled as shown to receive a cotter key 26, to secure the members 10 20 and 23 together.

An extension handle or fork 27 is detailed in Figure 4, and consists of a U-shaped fork 28 at the lower end of a pipe or rod 29, which may be made in sections, suitably jointed together. At 15 the upper end of pipe 29 is attached a T hand-grip 30. Extension handle 27 is preferably made entirely of pipe, as it must be capable of taking a thrust under certain conditions of use, and should be light in weight.

20 In operation, the lower end of guide cable 16 is attached to the framing at the bottom of the tank 12. This may be done before the tank has been freed of gas by an operator with a suitable mask, or may be done after steaming and ventilating without such precaution. The carrier guide 20, to which has been attached the nozzle fitting 23, carrying a suitable nozzle 31 and hose 32, is 25 then lowered down cable 16 by means of rope 33 until the assembly comes to rest on cable clamp 30 18 and washer 19, or to some higher position (not shown) as determined by the length of rope 33. Extension handle 27 is then placed in the position shown in Figure 1 with fork 28 straddling the stub shaft bearing 22.

35 Hot salt water from a ship's pump (not shown) is then turned into the hose 32, which immediately becomes semi-rigid as will be readily appreciated. A suitable method of obtaining hot water is by tapping the warm water discharge 40 from the ship's main condenser, and then heating this water to a higher temperature (150°-175° F.) by means of a steam injector of the conventional type. The hot salt water issues from the nozzle 31, and may be directed as desired about 45 a vertical axis, by means of the handle 27. Inclination of the nozzle 31 in a vertical plane about the stub shaft 25 is accomplished by the amount of semi-rigid pressure-distended hose 32 which is inside the tank. If it is allowed to assume a large 50 loop or bend adjacent the nozzle 31, the latter will be directed substantially vertically upward. If the hose is withdrawn so that there is no "slack" in the tank, the nozzle 31 will be pointed vertically 55 downward. Intermediate positions have been found to be surprisingly stable and the direction of the nozzle stream is at all times under the control of the operators, of which there are usually two, one for the orienting handle 27 and the other for the hose 32.

60 When the nozzle 31 is inclined above a horizontal plane through the stub shaft 25 the reaction is absorbed by the cable clamp 18, or by the rope 33, depending upon which is supporting the device. When the nozzle 31 is inclined downwardly, 65 or below a horizontal plane through the stub shaft 25, the reaction from the nozzle jet is upward and is absorbed by an operator through the extension handle 27. The weight of the operator is fully effective in absorbing this thrust, and a 70 heavy man can readily manipulate the device when the nozzle is pointing downwardly and the water pressure is over 150 lbs. per square inch.

75 It is obvious that numerous changes could be made in the arrangement just described, without departing from the essential features of the

invention. For example, guide cable 16 could be permanently attached to the bottom of the tank and provided with conventional securing and splicing means at its upper end so that it could be extended and the nozzle carrier apparatus threaded over it. Another modification would be the use of a rigid guide rod or bar in place of cable 16, said bar being permanently secured to the bottom of the tank 12, and detachably secured at its upper end near or in the hatch 10 opening. These arrangements would obviate the necessity for an operator entering the tank before it was freed from gas. Either the cable clamp 18 or the rope 33 could be dispensed with, and but one means employed for limiting the 15 downward travel and thrust of the device. If a single position of the device proved practicable for a given size of tank, the carrier 20 could be fixed to cable 16, or could be mounted between two clamps, thus causing the cable to take both 20 up and down thrusts and relieving the extension handle and its operator from all loads except that necessary to rotate the nozzle carrier assembly about the cable.

25 Although a specific construction embodying this invention has been described and illustrated, it is to be understood that the invention is not limited to that arrangement, and all such modifications and changes as come within the scope of the claims are embraced thereby.

30 I claim:

1. A tank cleaning device comprising a support 35 adapted to extend from the bottom of a tank to the top thereof, a nozzle pivoted on said carrier, orienting means for said carrier extending along and to the upper end of the support and adapted to move said carrier about said support as an axis, and a hose connected to said nozzle and adapted to supply a cleaning fluid 40 thereto, said hose adapted to be manipulated from the outside of said tank to move said nozzle in a vertical plane.

2. A tank cleaning device comprising a support 45 adapted to extend from the bottom of a tank to the top thereof, a nozzle carrier longitudinally movable on said support, a nozzle pivoted to move in a vertical plane on said carrier, orienting means for said nozzle extending along and to the upper end of the support and adapted to move 50 said nozzle about said support as an axis, and a hose connected to said nozzle and adapted to supply a cleaning fluid under pressure thereto, said hose adapted to hold said nozzle at a variable angle of inclination when said hose is under 55 pressure and is semi-rigid therefrom.

3. A tank cleaning device comprising a support 60 adapted to extend from the bottom of a tank to the top thereof, a nozzle carrier slidably mounted on said support, a nozzle pivoted on said carrier, a stop on said support below said carrier to receive the reaction of said nozzle along the line of said support, orienting means for said nozzle extending along and to the upper end of the support and adapted to move said nozzle about 65 said support, and a hose connected to said nozzle and adapted to supply cleaning fluid under pressure thereto.

4. A tank cleaning device comprising a support 70 adapted to extend from the bottom of a tank to the top thereof, a nozzle carrier rotatably mounted on said support, a nozzle on said carrier adapted to move about a substantially horizontal axis, a rope connected to said carrier to receive the downward reaction of said nozzle, orienting means 75

whereby said carrier and nozzle may be moved about said support as an axis, and a hose connected to said nozzle and adapted to hold said nozzle at a variable angle of inclination when said hose is in a semi-rigid condition under the pressure of cleaning fluid supplied to said nozzle.

5 5. A tank cleaning device comprising a cable adapted to be extended from the bottom of a tank to the top thereof, a nozzle carrier movably mounted on said cable, a nozzle pivotally supported on said carrier, a stop on said cable to receive a reaction of said nozzle along the line of said cable, orienting means extending from said nozzle carrier to a point outside of the tank whereby said carrier and nozzle may be moved about said cable as an axis and a hose connected to said nozzle and adapted to be manipulated from the outside of the tank to move said nozzle in a vertical plane.

10 6. A tank cleaning device comprising a cable adapted to be extended from the bottom of a tank to the top thereof, a nozzle carrier movably mounted on said cable, a nozzle on said carrier, a rope attached to said carrier to receive a downward reaction of said nozzle when said nozzle is pointed upwardly, orienting means extending from said nozzle carrier to a point outside of the tank whereby said carrier and nozzle may be moved about said cable as an axis and a hose 15 connected to said nozzle.

15 7. A tank cleaning device comprising a cable adapted to be extended from the bottom of a tank

20 to the top thereof, a sleeve slidably mounted on said cable, a bearing attached to said sleeve, a shaft secured in said bearing, said shaft fixed to a nozzle fitting, a nozzle secured to one end of said fitting, a hose secured to the opposite end of said fitting, a restraining clip on said cable to prevent motion of said sleeve along said cable from a reaction of said nozzle, and an extension handle adapted to engage said sleeve to orient said sleeve and nozzle about said cable as an axis.

25 8. A tank cleaning device comprising a guide adapted to extend from an opening in one wall of a tank to the opposite wall, a sleeve slidable on said guide, a bearing on said sleeve at right angles thereto, a shaft in said bearing, a hose connector attached to said shaft, a hose connected to one end of said connector, a nozzle connected to the other end of said connector, and a handle adapted to engage said sleeve to rotate said sleeve on said guide.

30 9. A tank cleaning device comprising a guide adapted to extend from an opening in one wall of a tank to the opposite wall, a sleeve slidable on said guide, means on said guide to limit the movement of said sleeve, a bearing on said sleeve at right angles thereto, a shaft in said bearing, a hose connector attached to said shaft, a hose connected to one end of said connector, a nozzle connected to the other end of said connector, and a handle adapted to engage said bearing to rotate said sleeve on said guide.

JAMES A. CRONIN.
